FOUNTAIN PEN

Xenophon W. Morgan, Erie, Pa.

Application November 25, 1947, Serial No. 787,947

3 Claims. (Cl. 120—46)

1

This invention relates generally to writing instruments and more particularly to fountain pens.

Conventional fountain pens now on the market generally leak when they are taken to an appreciable altitude such as in an airplane. When these prior pens are not in use, the ink in the feeding bar and the nibs of the pen tends to coagulate and harden with the result that feeding the ink to the point of the pen is stopped. It is necessary to shake the pen violently before these prior pens will feed. Pens now on the market have no means for varying the amount of ink being fed to the pen or increasing the pressure in the sack to increase the flow of ink thereto.

It is, accordingly, an object of my invention to provide a fountain pen which is simple in construction, efficient in operation, economical in cost, and economical in manufacture.

Another object of my invention is to provide novel filling means for a fountain pen.

Another object of my invention is to provide means for increasing or decreasing the flow of ink in a fountain pen.

Another object of my invention is to cover substantially the entire pen point or nibs on a fountain pen to prevent coagulation of ink thereon.

Another object of my invention is to provide novel feeding means for a fountain pen.

Another object of my invention is to provide a novel fountain pen wherein the ink does not leak therefrom.

Other objects of my invention will become evident from the following detailed description, taken in conjunction with the accompanying drawings, in which

Fig. 1 is a side elevational view of my novel fountain pen with parts thereof broken away for better illustration thereof;

Fig. 2 is a fragmentary vertical section taken through the center line of the fountain pen shown in Fig. 1;

Fig. 3 is a side elevational view of my novel fountain pen;

Fig. 4 is a view taken on the line 4—4 of Fig. 2;

Fig. 5 is a view taken on the line 5—5 of Fig. 2;

Fig. 6 is a fragmentary vertical sectional view of a modification of my fountain pen shown in Figs. 1 and 2; and

Fig. 7 is a fragmentary sectional view of another modification wherein different means are provided to secure the pen parts against relative longitudinal movement.

Referring now to the drawings, I show in Figs.

2

1, 2, 3, 4, and 5 a barrel 1 internally threaded at 2 to threadably engage the reduced threaded end 3 of a cylindrical sleeve 4. The sleeve 4 has an inwardly projecting portion 5 and a roughened portion 6 on one side thereof. A tapered head 7 with a bore 8 has a reduced connecting portion 9 for insertion in and connection to the sleeve 4. The end 9 of the head 7 has a stop portion 10 for engaging the stop member 5 of the sleeve 4 so that the head 7 will make less than one revolution. The head 7 has an aperture 12 for receiving a pin 13 and a spring 14, the pin 13 frictionally engaging the roughened portion 6 of the sleeve 4 whereby the head 7 may be rotated and frictionally held in any position by the pin 13. The pin 13 has connected thereto a finger button 15 by which it may be drawn out of frictional engagement with the roughened portion 6 of the sleeve 4 when it is desired to rotate the head 7 a full revolution in the filling of the pen. A feeder sleeve 16 is disposed in the bore 8 of the head 7 and has connected thereto a sack 18 for holding ink. The sack 18 is connected to the feeder sleeve 16 by cementing or any other suitable means at 19. A conventional longitudinally grooved feeder bar 20 is disposed on the end of the feeder sleeve 16 and a conventional pen point 21 is disposed between the feeder bar 20 and the inner side of the bore 8 of the head 7. Pen point 21 is of conventional type with eye 22 and adjacently disposed tapered nibs 23. An elastic cup-shaped member 24, preferably made of a flexible rubber, has an aperture 25 therein into which extend the nibs 23 of the pen 21. The member 24 is cemented to the inner side of the head 7 at 26 as shown in Figs. 1 and 2.

The opposite end of the barrel 1 has a reduced threaded portion 30 for receiving the internally threaded portion 31 of a cap member 32. A shoulder 33 is formed in the cap member 32 to engage the outwardly flanged end 34 of the sack 18 which is preferably cemented to the end of the barrel 1. A filler member 35 extends into the recessed portion 36 of the cap 32 and it has an enlarged end 37 which is cemented to the inner side of the sack 18. The cap member 32 has a sealing member 38 of rubber or like suitable material which seals the end of the filler member 35 when the sack 18 is not being filled and the pen is in use.

In the filling of my novel fountain pen, the cap member 32 is removed from the end of the barrel 1, the button 15 is moved by the finger causing the pin 13 to move out of frictional engagement with the roughened portion 6 of the sleeve 4 and

the head 7 is rotated almost one revolution until stop portion 10 on the head 7 engages the stop member 5 on the sleeve 4. When the head 7 turns, the sack 18 is twisted and all of the air therein is expelled. The head 7 is then rotated in a reverse direction as far as it can be moved with reference to the stop members 5 and 10 while the filler end 35 is dipped in ink. The un-twisting of the sack 18 will permit the ink to move therein and fill the sack 18. When the sack 10 is filled, the cap member 32 is threadedly engaged to the threaded end 39 of the barrel 1 and the filler member 35 is sealed by the sealing member 38 in the cap 32. In the operation of the fountain pen, the head 7 is rotated slightly to increase the pressure on the ink in the sack thereby forcing it outwardly to the feeding bar 20 and the nibs 23 of the pen 21 and through the aperture 25 in the flexible cup-shaped member 24. It has been found that with a slight twist of the head 7, twenty sheets of paper may be written with my novel fountain pen before further rotation of the head is required. The pen is always ready for use and no ink dries or coagulates and thereby stops up the end of the pen 21. A spring 25 clip 90 secures the portions 7 and 4 against relative longitudinal movement.

In Fig. 6 I show another form of my novel pen similar to the pen shown in Figs. 1 and 2 except that a ball member is provided to permit self feeding of the pen. In this construction only the structure of the head differs from that shown in Figs. 1 and 2, barrel 1, sleeve 2, and cap 32 being the same. In Fig. 6, head 50 has a bore 51 and a laterally extending aperture 52 in the bottom side of the head 50. The feeder bar 53 has a tapered apertured portion 55 for receiving a ball member 56. A conventional type pen 57 and cover member 58 similar to those in Fig. 1 are disposed in the head 50. All other parts of head 50 are the same as those shown in the head 7 of Figs. 1 and 2. The general operation of my pen shown in Fig. 6 is the same as the pen shown in Figs. 1 and 2 except that the ball member 56 normally sealingly engages the laterally extending aperture 52 when the pen 57 is in a writing position and it is held downwardly. When it is desired to permit air to enter the feeding bar 53, the pen 21 is held upwardly and the ball member 56 will move out of sealing engagement with the laterally extending aperture 52 in the head 50 and air will enter therein.

Fig. 7 shows the barrel 70 having a threaded portion 71 for engagement with the threaded portion 72 of intermediate portion 73. Nose portion 55 74 is secured against relative longitudinal movement by an annular ring 75 cemented to projection 76 thereof. The ring 75 engages a shoulder 77 of intermediate portion 73.

It will be evident from the foregoing description that I have provided a novel fountain pen which always keeps the pen point free of coagulated and dry ink, which is always ready for operation and use, which permits the ink to flow freely, and which does not permit leakage and escape of ink due to changes of altitude or any other change of pressure or for any other reason.

Various changes may be made in the specific embodiment of my invention without departing from the spirit thereof or from the scope of the appended claims.

What I claim is:

1. A fountain pen comprising a barrel, a threaded sleeve for engaging said barrel, a bored tapered rotational member engaging said sleeve and rotatable relative thereto, a feeding bar in said rotational member, a pen having tapered nibs extending outwardly from said rotational member, an elastic flexible member sealingly engaging the end of said rotational member and the nibs of said pen, the ink feeding through said nibs of said pen to the point thereof when said point of said pen is pressed upon a writing surface, a sack connected at one end with said feeding bar and rotatable with said rotational member, a filler member on the opposite end of said sack, and means for sealing said filler member.

2. A fountain pen comprising a barrel, a rotatable bored head connected to said barrel, stop means for limiting the rotation of said head relative to said barrel, a pen having tapered nibs extending outwardly from said rotatable head, flexible elastic sealing means for the end of said barrel sealingly engaging a point laterally of the nibs of said pen and the end of said head, said ink flowing through the nibs of said pen to the point thereof past said sealing member when the point of said pen is pressed against a writing surface, a sack rotatable with said rotatable member and secured at one end to the opposite end of said barrel, a filling member secured to the other end of said sack, a cap for the end of said barrel, and a sealing member in said cap for sealing the end of said filling member.

3. A fountain pen as set forth in claim 2 wherein engageable frictional members are disposed on said barrel and said rotatable member to frictionally secure said rotatable member at any predetermined rotational position.

XENOPHON W. MORGAN.
